TIME PRINTING DEVICE

Ernest S. Ostler, Chicago, Ill., assignor, by mesne assignments, to General Time Instruments Corporation, New York, N. Y., a corporation of Delaware

Application January 11, 1933, Serial No. 651,243

22 Claims. (Cl. 101—287)

My invention relates to time printing devices and more specifically to electrically operated time stamps.

This application is a continuation in part as to all of the subject matter of my co-pending application, Serial No. 481,325, filed September 11, 1930, for Time printing device. It also contains certain additional subject matter claimed herein.

One of the objects of my invention is to provide an improved time stamp in which the insertion of the paper to be stamped controls the stamping operation.

A further object is to provide a construction in which the controlling switch is opened and latched in open position by the stamping operation.

A further object is to provide a construction in which the actuation of the paper controlled trip will not cause a repetition of the closing of the switch except upon the reinsertion of the paper or the insertion of a new paper.

A further object is to provide a construction in which uniform contact-making action is obtained regardless of the manner in which the paper to be stamped is inserted.

A further object is to provide a construction in which the circuit is broken before the stamp head strikes the platen.

A further object is to provide an electric stamp mechanism which will use a comparatively small amount of current.

A further object is to provide a construction which will minimize the danger of the stamp controlling switch being held in closed position longer than necessary.

A further object is to provide a construction in which the sub-assemblies are easily removable and replaceable.

A further object is to provide a construction in which the magnet which controls the printing wheels is carried in vertical position in the oscillatable frame.

A further object is to provide a construction in which the cover may be removed easily and the stamp head raised to permit access to the lower face of the stamp head for changing the ribbon.

A further object is to provide a construction in which the removal of the cover releases the limiting stops so that the stamp head may be swung up to change the ribbon and in which the replacement of the cover returns the stamp head to normal operating position.

55 A further object is to provide a construction in

which the various parts are readily accessible for inspection, removal and replacement.

A further object is to provide a construction in which the impression member has a yielding connection with the plunger of the electro-magnet to permit the plunger to complete its movement even if the movement of the impression member should be obstructed.

A further object is to provide a construction in which the ribbon feed mechanism is actuated on the upstroke of the stamp head, thus not interfering with the stamping movement.

A further object is to provide a slip-drive for both the hour and dating wheels, the slip-drive for the hour wheel being powerful enough to drive both the hour and the dating wheel.

A further object of the invention is to provide a contact-making device which requires only a small fraction of the pressure or energy in closing, as compared with the pressure at the contact points or the energy expended in closing. It is not my intention to confine the above feature of the invention to use on a time stamp or a printing device.

A further object is to provide a construction in which the cover may be unlocked from either side.

A still further object is to provide means for varying the force of the impression blow.

Further objects will appear from the description and claims.

In the drawings in which an embodiment of my invention is shown:

Figure 1 is a perspective view of the time stamp;

Fig. 2 is a horizontal sectional view through the oscillatable frame on the line 2—2 of Fig. 6;

Fig. 3 is a vertical fore and aft sectional view substantially on the line 3—3 of Fig. 4;

Fig. 4 is a transverse sectional view substantially on the line 4—4 of Fig. 3;

Fig. 5 is a plan view of the lower casing or frame section with parts carried thereby, the cover and stamp head being removed;

Fig. 6 is a vertical fore and aft section showing the stamp head and associated parts substantially on the line 6—6 of Fig. 4;

Fig. 7 is a detail side elevational view showing the switch and associated parts;

Fig. 8 is a detail elevational view of the parts shown in Fig. 7 as seen from the right;

Fig. 9 is a view similar to Fig. 7, but showing the switch closed;

Fig. 10 is a perspective view showing certain parts of the paper controlled mechanism for latching and releasing the switch;

- Fig. 11 is a vertical fore and aft sectional view of the stamp head on the line 11—11 of Fig. 2;
 Fig. 12 is a side elevational view of the hour wheel;
 5 Fig. 13 is an edge view thereof;

 Fig. 25 is a side elevational view of a somewhat different form of switch and controlling 30 mechanism;
 Fig. 26 is a view from the left of Fig. 25;
 Fig. 27 is a perspective view of a part of the switch-controlling mechanism;
 Figs. 28 and 29 are detail perspective views of 35 alternatively usable trip fingers;
 Fig. 30 is a detail view showing the yielding connection between the armature 134 and the stamp head 3;
 Fig. 31 is a central vertical section of a stamp 40 embodying the switch control shown in Figs. 21 to 24, inclusive;
 Fig. 32 is a detail view showing the connection between the armature and the switch controlling pin; and
 45 Fig. 33 is a detail enlarged view showing the cam adjustment for the pin-carrying bracket.
 I will first outline briefly the construction and operation before describing it in detail.
- The time stamp shown comprises a two-part 50 casing having an upper section 1 and a lower section 2 separable substantially on a horizontal plane (the upper section being in the form of a readily removable hood for exposing and permitting access to the stamp head), a time controlled, time printing stamp head 3 oscillatable up and down in the upper casing section and pivotally mounted at 4 adjacent to the upper rear end of the lower section, a vertically movable plunger 5 (Figs. 6 and 31) connected with said 55 stamp head in front of its pivotal mounting, a solenoid coil 6 (Figs. 3 and 31) in the lower casing section in which the plunger operates for drawing the stamp head to effect stamping action of the stamp head, printing wheels, ribbon feed mechanism and clock mechanism mounted on the front end of the stamp head, a vertically operating plunger 7, and a solenoid coil 8 mounted on the rear end of the stamp head for 60 periodically advancing the printing wheels in a time controlled manner, transmission from said plunger to said printing wheels, a switch 9 (Figs. 6 and 7) in the lower casing section for controlling the circuit of the stamp head operating solenoid, a spring 10 tending to close this switch 65 mechanism, means controlled by movement of

the solenoid plunger for setting and latching the switch in open position against the action of the spring, mechanism controlled by the edge of the paper to be stamped for releasing the latch 11 to permit the spring 10 to close the switch, a second switch 12 (Figs. 3 and 5) in series with the first switch for controlling the circuit for the solenoid coil 6, this latter switch being controlled by the act of placing the upper casing section 1 in position and being provided with a 10 spring which will throw it to open position when the cover is removed, thus preventing any danger of the solenoid coil being energized when the hood is removed.

In operation, the switch 9 and the switch controlling mechanism are normally in the position shown in Fig. 7. When the edge of the paper to be stamped is inserted in the machine, it engages the trip or trigger lever 14 and moves it to the left, thereby releasing the switch and 20 permitting the contacts 19 and 88 to close under the action of the coil compression spring 10 (Fig. 9).

This closing of the switch energizes the solenoid coil 6 and draws the stamp head down to print 25 the time on the inserted paper.

On the downward movement of the solenoid plunger 5 the pin 20 (Figs. 6, 7 and 9) carried by the plunger engages the switch-opening and resetting arm 21, opening the switch against the 30 action of the coil compression spring 10 and causing the switch to be re-latched in open position. This opening of the switch should occur a short time before the stamp head actually strikes the paper so that the stamping action actually 35 takes place due to the momentum of the stamp head and associated moving parts.

The opening of the switch de-energizes the solenoid coil so that immediately after the printing wheels strike the paper the stamp head will 40 be returned to its raised position under the action of the restoring spring 22 (Figs. 4 and 6). Upon the withdrawal of the stamped paper, the latch-releasing trip lever 14 will be returned to its original position, as shown in Fig. 7, under the 45 action of the trip-returning tension spring 23. As will be explained more in detail hereinafter, no repetition of the closing action of the switch will occur if the paper should be left holding the trip in latch-releasing position, but the paper 50 must be withdrawn to permit the trip to return to initial position before it can again be used to unlatch the switch to permit it to close.

Coming now to the operation of the electromagnetic means for periodically advancing the 55 time printing wheels and clock mechanism (Figs. 3 and 6), a master circuit controller (not shown) is provided which periodically energizes the solenoid coil 8 which controls the printing wheels and clock by means of pawl and ratchet mechanism to be explained later. The frequency of this energization will depend on the particular style of time printing mechanism provided. In the form shown, this energization will occur once every six seconds, that is to say, ten times during 65 the minute, as the style of stamp shown comprises a printing wheel for printing tenths of a minute.

In the type of stamp shown there are five printing wheels driven and locked in train from 70 the driving ratchet wheel. The five wheels as shown in Fig. 2 comprise the printing wheel 28 for printing the tenths of a minute, the units minute wheel 29, the tens minute wheel 30, the hour wheel 31, and the dating wheel 32. These 75

wheels are driven and locked in train by means of Geneva gear movements.

The month wheel 33 and the year wheel 34 are not driven from the ratchet wheel but are independently set by means of the setting shaft 35 and an operating key which engages the flattened end 36 of the setting shaft.

As will be explained more in detail hereinafter, means are provided for setting both the hour 10 wheel and the dating wheel independently of the minute wheels, still permitting both of these wheels to be driven in train from the ratchet wheel in the normal operation of the printing wheel advancement.

15 In order to insure that the circuit for the stamp-actuating solenoid is broken when the hood is removed and closed when the hood is in position, a circuit controlling switch 12 (Fig. 3) is mounted on the frame which carries the 20 solenoid coil 8 having a push button 37 located in position to be engaged by the lower end of a pin 38 mounted on the cover 1, so that when the cover is placed in position the lower end of this pin 38 will press down on the push button and 25 close the switch. When the cover is removed, the pin will be moved away from the push button and a spring (not shown) will throw the switch to open position.

In order to hold the cover securely in position 30 on the lower casing section 2, a pair of pivoted spring latch members 39 are provided for engagement with keeper members 40 mounted on the cover. When the cover (Figs. 3 and 5) reaches its final position, these hook-like latch 35 members snap over the upper edges of the keeper members to hold the cover in position. To release the cover, a key is provided which can be inserted in a keyhole 41 (Fig. 1) in the lower casing section to engage the flattened end 42 of 40 an oscillatable cam shaft 42^a on which are mounted a pair of cams 43 engaging the downwardly extending arms 44 of the latch members. When this cam shaft is rocked, the cams unlatch 45 the latch members against the action of the coil springs 45 to permit the removal of the cover.

In order to provide a solid reliable limiting means for the return movement of the stamp head, I provide a pair of stop members 46 rockably mounted at 47 adjacent the upper rear end 50 of the lower casing section (Figs. 3 and 5), these stop members being automatically moved to effective position by the act of placing the cover in position on the lower casing and being automatically moved to non-effective position upon 55 the removal of the cover. This control of the pivoted limiting stops 46 is effected by means of a pair of operating blocks 48 (Fig. 3), the lower edges of which engage the rear edges of the limiting stop members when the cover is 60 being placed in position to force these pivoted stop members to the position shown in Fig. 3 in which they are located in the path of the stop pins 49 on the oscillatable stamping frame.

When the cover is removed, the springs 45 65 which extend between the arms 44 and the downward extensions of the stop members 46 will move the stop members 46 to non-effective position so that the stamp head may be swung up to permit inspection and changing of the ribbon.

70 In order to guide the cover in placing it in position on the lower casing section, thus insuring the proper engagement of the latched members 39 with the keeper members 40 and of the block members 48 with the pivoted stop members 46, three dowel pins 50 (Figs. 3 and 5) are

provided firmly secured to the lower casing and engageable with the dowel openings in the cover.

Details of lower casing section and mounting for associated parts

The lower casing section 2 is provided with a horizontal support or shelf 51 (Fig. 6) on which is mounted a rubber platen 52 which cooperates with the printing wheels. A cover plate 53 is provided above this shelf 51 having an opening 10 registering with the platen 52. On this cover 53 are mounted a pair of pivoted pressure arms 54 underneath which the edge of the paper slides when it is inserted for stamping. These pressure arms 54 are pivotally mounted at 55 on 15 upwardly extending ears 56 formed integral with the cover plate 53. In order to limit the pivotal movement of these pressure arms 54 they are provided with downwardly extending arms 57 which engage with the edge of the lower casing 20 to prevent too great movement. In order to limit the distance to which the edge of the paper can be inserted a pair of stop pins 58 (Fig. 5) are secured to the cover plate 53.

The bracket 61 for the paper controlled switch 25 is mounted on the under side of the shelf 51 by means of screws 59 extending through a horizontal flange 60 on the switch bracket 61 and threaded into the shelf 51 (see Figs. 7, 8 and 9).

The solenoid coil 8 and the safety switch 30 mounted on the frame of the solenoid coil are secured inside of the lower casing section by means of four screws 62 (Figs. 3 and 4) extending through horizontal flanges 63 or lugs on the coil supporting frame and threaded into downwardly 35 facing bosses 65 formed integral with the lower casing section 2. The pivoted latch members 39 are mounted on the shaft 4 (Fig. 3) extending from one side to the other of the lower casing section 2 and having its ends secured in openings 40 in the upwardly extending lugs 67. The pivoted stop members 46 for limiting the movement of the stamp head are rockably mounted on inwardly extending studs secured in the upwardly extending ears 68 on the lower casing section. 45 The pair of springs 45 serves to control both the pivoted latch members 39 and the pivoted stop members 46, these springs extending from the downwardly extending arms 70 on the stop members 46 to the downwardly extending arms 44 50 on the latch members. In order to limit the movement of the pivoted stop members a pair of stop pins 71 are mounted in the upwardly extending flanges 72 of the lower casing section 2. (Figs. 3 and 5). 55

Wiring.

The wiring for the printing wheel controlling solenoid 8 comprises a pair of wires 73 (Fig. 4) leading through an opening in the rear of the lower casing section to a pair of binding screws 74, and a pair of wires 75 leading from these binding screws to the solenoid coil 8. These binding screws are mounted on an insulating plate 76 secured to a downwardly facing shoulder on the lower casing section 2 by means of a pair of screws 77 (Figs. 1 and 4).

The wiring for the stamp head actuating solenoid 6 comprises a pair of feed wires 78 (Figs. 3 and 19) leading through an opening in the rear end of the lower casing section to a pair of binding screws 79 (Figs. 4 and 19), a wire 80 (Figs. 7 and 19) leading from one of these binding screws to one of the binding terminals 81 for the paper controlled switch, a wire 82 leading from the other binding screw 83 of the paper controlled 75

switch to one side of the safety switch 12, a wire 84 leading from the other side of the safety switch to one side of the solenoid coil, and a wire 85 leading from the other side of the solenoid coil 5 to the other binding screw 79. The binding screws 79 are mounted on an insulating plate 86 secured to a downwardly facing shoulder on the lower casing section by means of a pair of screws 87 (Figs. 1 and 4).

10 *Details of paper controlled switch*

In time printing devices it is highly desirable that the stamping action should be uniform in order to secure uniform printing. In order to 15 secure uniform stamping and printing action I provide a switch construction (Figs. 7 to 10) in which the contact-making action is substantially uniform, no matter whether the manual action which results in the contact-making action is 20 made quickly or slowly. For this purpose I provide a spring for closing the switch and a retaining latch for holding it open, which automatically releases the switch to permit it to close under spring action when the paper is inserted. The 25 switch-closing action, and consequently the amount of current supplied to the solenoid, will thus be the same regardless of the speed with which the paper is inserted.

The moving parts of the paper controlled 30 switch comprise a slidably mounted contact member 19 for cooperation with the stationary contact member 88, the slide-actuating switch arm 18 oscillatably mounted on a shaft 89 extending between the side frame members 61 and 90, a 35 switch arm operating member 21 also rockably mounted on the shaft 89 (Figs. 7 and 9) and having a lost motion spring connection with the switch arm, a latch member 11 pivotally mounted on a stud 91 secured to the actuating rock 40 member 21, a spring pressed keeper member 13 (Figs. 7, 9 and 10) rockably mounted on a stud 92 secured to the frame member 90, a stop pin 93 for limiting the spring pressed movement of the rockable keeper member and also of the latch 45 member 11, the paper controlled trigger 14 rockably mounted on a shaft 94 extending between the side frame members 61 and 90, and the latch-releasing hook 15 pivotally mounted on a shaft 95 extending between the trigger arm and 50 a frame plate 96 secured to the trigger arm 14 by means of a pair of pins 97. A coil tension spring 98 is provided which tends to hold the arm of the rockably mounted keeper 13 in engagement with the stop pin 93 on the side frame. 55 Another coil tension spring 99 (Fig. 9) is provided secured to the pivotally mounted latch member 11 and tending to hold the edge 16 of this pivotally mounted latch member over against the laterally extending arm 100 of the keeper member 13. 60 Another coil tension spring 23 (Fig. 7) is provided which serves as a returning spring for the rockably mounted trigger arm 14 when the edge of the paper is withdrawn, this spring having one end secured to the frame plate 96 on the trigger 65 arm and its other end secured to a stud 101 on the side frame 90. The side frame members 61 and 90 are secured together and held in proper spaced relation by means of the shafts extending therebetween and a pair of spacing and se- 70 curing rods 102 extending from one side frame to the other. One of these spacing members serves as a stop for the trigger member by reason of the engagement therewith of the rearwardly extending arm 103 on the trigger (Fig. 7).

75 When a sheet of paper which is to be stamped

is inserted into the mechanism, the trigger member 14 is moved toward the left as seen in Figs. 7 and 9 and carries with it the latch releasing hook 15. The hook edge 106 of the latch releasing hook 15 is in engagement with 5 the lateral arm 105 of the latch member 11 and the movement of the trigger arm therefore rotates the latch member 11 in a clockwise direction about its pivot point 91, thus causing the latching edge 16 of latch member 11 to disengage from latching edge 17 on the laterally extending arm 100 of the keeper member 13. The switch arm operating member 21 and the switch arm 18 are now free to rotate clockwise about the shaft 89 under the urgency of coil compression spring 10. The engagement of contacts 19 and 88 completes the circuit to the operating magnet of the time stamp.

An inspection of Figs. 7 and 9 will show that when the latch 11 disengages the keeper 13, as 20 above described, the stud 91, which carries the latch 11, will move downwardly about the shaft 89 as an axis, as the switch arm 18 rotates clockwise. This moves the arm 105 out of engagement with the hook 15, which (as pointed 25 out in detail later) is held against downward movement. When the arm 105 disengages the point 106 of the hook 15, it snaps slightly to the right (as viewed in Fig. 9) under the action of the spring 99, as will be brought out more fully 30 later.

Referring again to the latch releasing hook 15, it will be seen that this hook is mounted on a shaft 95 which is carried between and has its bearings in the trigger arm 14 and a mounting 35 plate 96. The plate 96 is held in spaced relation to trigger arm 14 by means of pillars 97. It will also be seen from the drawings that the latch releasing hook 15 is provided with a downwardly extending bumper tail designated as 15a. This 40 bumper tail lies in close proximity to the hub of the lower pillar 97.

When the trigger arm 14 is rotated counter-clockwise around the pivot point 94 by the insertion of a sheet of paper into printing position, the shaft 95 which mounts the latch releasing hook 15, being above the lower pillar 97 on the trigger arm 14, moves a greater linear distance than the lower pillar 97. Thus when the trigger arm 14 has been moved a short distance 50 to the left, the bumper tail 15a of the latch releasing hook 15 comes into engagement with the hub of pillar 97 and will thereafter prevent any downward movement of the hook 15, until the trigger arm 14 is released and allowed to 55 move to the right. Shortly after the bumper tail 15a engages the pillar, the latch 11 disengages the keeper 13 and the switch closes under the action of the spring 10. As the switch closes, the stud 91 moves downwardly, moving 60 the latch 11 downwardly also to disengage the arm 105 from the hook 15, which (as pointed out above) is held against downward gravitational movement because of the engagement of the bumper tail 15a with the pillar. Also, when 65 the arm 105 slips off the point of the hook 15, it snaps slightly to the right (as shown in Fig. 9) under the action of the spring 99.

Thus when the trigger arm 14 has completed its movement to its left hand position, the latch 70 member 11 has been moved to the left to disengage latching edge 16 from latching edge 17, thereby allowing the contacts to close as previously explained and at the same time the hook 15 has been held in raised position by the abut- 75

ment of bumper tail 10a against the hub of the lower pillar 87 so that the latch member 11 is free to return to its right hand position without engaging or coming in contact with the hook 15. Fig. 9 of the drawings clearly shows this point in the cycle of operation. The switch arm 18 has been released, the contacts 19 and 88 are closed and the hook 15 is held raised and has allowed the latch member 11 to return to its right hand position.

The closing of the contacts 19 and 88 completes the circuit to the electromagnetic mechanism bringing about the operation of the stamp head. During this operation the pin 20 or soleiloid plunger 5 rotates the switch operating arm 21 in a counterclockwise direction about its pivot point 88. The switch arm 18 is thereby returned to its normal position with contacts 19 and 88 open and the latch member 11 is raised by its mounting pin 91 until its latching edge 16 is above the latching edge 17 of keeper 13. The spring 99 then rotates latch member 11 in a counterclockwise direction so that the latching edge 16 again engages latching edge 17 to hold the switch in its open position.

I will now explain the purpose of mounting the keeper member 13 in a manner permitting a slight oscillation thereof. This is to insure relatching of the paper controlled switch in open position upon the actuating of the switch returning arm 21, even if the paper should be left in a position to prevent the return of the trigger arm 14. In explanation of this, it will be seen that if the keeper member 13 were not permitted to yield under the pressure of the edge of the latch member against the arm 100, and if at the same time the trigger arm 14 were not permitted to return under the action of the spring 23, the edge 104 of the lateral arm 105 of the latch 11 would move into engagement with the edge 106 of the hook 15 on the opening movement of the switch arm and the latching edge 16 of the latch member would thus be prevented from engaging with the latching edge 17 of the keeper member 13. However, because of the yielding rockable mounting of the keeper member 13, the arm 107 of the keeper member will be rocked away from the limiting stop pin 93 because of the pressure of the edge of the latch member against the surface of the laterally extending finger 100 of the keeper member (the tension of the spring 99 for the latch member being strong enough to overcome the tension of the spring 98 for the keeper member). This yielding of the keeper member permits the hook-engaging edge 104 of the latch member to swing free of the point 106 of the latch-releasing hook 15 (in the situation assumed in which the paper is preventing the return movement of the trigger arm and the hook 15 carried thereby). Thus, the switch member properly relatches when moved to open position by the switch opening arm 21 regardless of whether or not the paper controlled trigger arm 14 has been allowed to return.

The closing movement of the switch arm is effected by means of the coil compression spring 10 extending between a shoulder 107a on the contact carrying slide 108 and a lug 109 on the slide-carrying bracket 110. The contact-carrying slide 108 is slidably mounted on the bracket 110 by means of a pair of rivets 111 extending through slots 112 in the slide and secured to the flange 113 of the bracket 110. The slide carrying bracket 110 is, in turn, riveted to a mounting bracket 114 seated in a recess in an insulating

block 115 to which it is secured by means of a screw 116. This insulating block is secured to the side frame by means of screws 117. The binding screw 83, previously referred to, is screwed into a laterally extending lug 118 formed integral with the mounting bracket 114. The circuit from this binding screw 83 to the movable contact 18 is through the mounting bracket 114, slide-carrying bracket 113 and either the slide 108 itself or slide-actuating spring 10 to the clip 10 119 which embraces the contact member 18. The stationary contact member 88 is mounted in a clip member 120 secured to a lug 121 extending from a mounting bracket 122 secured in a recess in the insulating block 113 by means of a screw 15 123. The other binding screw 81, previously referred to, is threaded into a lug 124 formed integral with the mounting bracket 122.

The yielding lost motion connection between the switch arm 18 and the actuating member 21 20 permits the actuating arm 21 to have its full movement even if the switch arm for any reason should stick and refuse to move to open position, thus preventing injury to the mechanism. This yielding connection also permits the actuating 25 arm 21 and pin 20 to have their full movement without any interference on account of the limited movement of the slide 108. The coil compression spring 125, which provides the yielding connection, has one end centered by means of a pin 126 secured to a laterally extending lug 127 on the switch arm 18, and its other end centered by means of an upwardly extending finger 128 on the actuating arm 21. The separating action of the compression spring 125 is limited by the laterally extending lug 129 on the arm 18 engageable by the edge of the actuating arm 21. The spring 125 also serves to cushion the effect of the blow of the pin 20 on the switch arm 18.

Stamp head actuating solenoid

40

The solenoid coil 6 is embraced by a U-shaped pole piece 130 formed of laminated plates and secured between the mounting brackets 131 by which the coil is mounted on the lower casing section and on which brackets the coil 6 itself is mounted. The coil is held in position by means of clips secured to the mounting brackets 131 and having horizontally extending fingers 132 extending over the fibre plate 133 (Figs. 4 and 5) 50 secured to the inner shell of the coil. The upper end of the coil is positioned or centered by means of the edges of the brackets 131 engaging the edges of correspondingly-shaped notches in the fibre disc.

55

The plunger member 5 comprises a portion operating in and surrounded by the coil 6 and a transversely extending armature portion 134 cooperating with the ends of the pole pieces 130 and is built up of laminated plates secured together 60 by rivets.

65

The yielding connection between the plunger 5 and the stamp head is effected by means of a yoke member 134a having upwardly extending arms 135 (Figs. 2, 4, 6, 30 and 31) provided with bearing members 136 engaging inwardly extending bearing pins 137 on the side frame members 138 of the stamp head, a coil compression spring 139 having its lower end positioned and centered by a plate 140 secured to the yoke by a screw, an 70 adjustable abutment 141 against which the upper end of the spring bears, slidably mounted in guide plates 142 riveted to the plunger, and an adjusting screw 143 swiveled on the inwardly extending flanges 144 of the guide plates and hav- 75

ing a threaded engagement with the slideable abutment 141. In order to hold the swiveled screw 143 in any position to which it may be adjusted, a pin 145 is provided extending transversely through the swiveled screw, the ends of this pin being movable into the space between the inwardly extending flanges 144. In order to adjust the slideable abutment 141, a screw driver is applied to the upper end of the swivel adjusting screw 143, the pressure being applied axially at first, to move the ends of the retaining pin 145 from the space between the ends of the flanges 144, and the screw driver then being turned to give the desired adjustment to the slideable abutment 141. When the desired adjustment has been secured the swivel screw is turned just enough to bring the ends of the retaining pin into registration with the space between the flanges 144, whereupon the coil compression spring 139 will force the swivel adjusting screw upwardly to bring the ends of the retaining pin into the space between the flanges, thus holding the swivel adjusting screw in properly adjusted position.

The switch opening pin 20 is riveted to an L-shaped bracket 146 which, in turn, is riveted to the guide plate 142 (Fig. 6).

In operation, if, for any reason, the stamp head should be prevented from having a movement of sufficient extent or speed to keep up with the plunger, the yieldable compression spring 139 will permit the plunger 5 to travel ahead of the yoke 134^a, against which the lower end of the compression spring bears. This yielding connection would enable the plunger 5 to continue its movement and open the switch even if the stamp head should be held against movement (for instance, by the insertion of a pad underneath the stamp head which might be so thick as to prevent or interfere with downward movement of the stamp head).

Stamp head printing wheels and clock mechanism

The stamp head 3 is oscillatably mounted on the same shaft 4 as that on which the pivoted latch members 39 are mounted. The return movement of the stamp head is effected by means of the coil compression spring 22 acting on a plunger 147 (Figs. 4 and 6) slidably mounted in an opening 147^a (Fig. 5) in an inwardly extending lug 148 on the lower casing section and pivotally connected at its upper end with a pin 149 extending between the arms of a yoke 150, the arms 151 of which are provided with bearing members 152 to receive the inwardly extending journal studs 153 mounted on the side plates 138. The upper end of the compression spring 22 bears against and is positioned by a flanged sleeve 154 through which the plunger extends, the flange of this sleeve bearing against the under side of the guide lug 148. The lower end of the spring 22 bears against and is centered by a flanged sleeve 155 through which the plunger 147 extends, this sleeve being held on the plunger by means of an adjusting screw 156 threaded on the lower end of the plunger 147. This adjusting screw may be held in adjusted position by means of a cotter pin 157 extending through a slot in the end of the screw.

The solenoid coil 8 and associated parts for operating the actuating lever 27 for the printing wheels and clock mechanism may be, in general, of the same construction as that for controlling the stamping action, previously described,

including the laminated yoke-shaped pole piece 158 and the T-shaped plunger 7, the ends of the cross arm of which extend between the forked ends 159 of the side plates 138 and 181 of the actuating lever 27 (Figs. 2 and 6). The actuating lever is rockably mounted on a shaft 162, the ends of which are mounted in the side plates 138 of the stamp head. The side plates of the actuating lever are secured together and held in spaced relation by means of pins 163, the ends of which are riveted to the side plates. The side plates of the stamp head itself are secured together and held in proper spaced relation by means of rods 164 extending between the side plates and secured thereto. The actuating lever 27 is returned when the solenoid is de-energized by means of the coil tension spring 24, one end of which is secured to a stud 165 on the actuating lever and the other end of which is secured to a stud 166 on the side plate.

Printing wheel mechanism

Each actuation of the lever 27 advances the printing wheel mechanism one step. In the type shown, each step corresponds to one tenth of a minute. Therefore, the coil 8 should be energized ten times per minute advancing the tenths minute wheel 28 one step for each energization. When the coil 8 is energized it moves the lever 27 from the dotted line to the full line position shown in Fig. 6. This movement retracts the actuating pawl 25 and causes it to engage the next succeeding tooth of the ratchet 26. When the coil 8 is de-energized the spring 24 returns the lever 27 to the dotted line position and advances the ratchet wheel 26 one step. The ratchet wheel 26 is held against movement and prevented from overthrow movement by engagement of the pin 167 on the lever 27 with the sloping face of a tooth on the lock and clutch wheel 168. The ratchet wheel is locked when the lever 27 is in the full line position of Fig. 6 by the engagement of the pin 169 on the lever 27 with the inclined edge of the upper end of the locking lever 170. This action holds the locking lever in the position shown in Fig. 6 in which the non-return pin 171 on the locking lever 170 is held snugly in engagement with the ratchet wheel 26. This locking lever is pivotally mounted on a rock shaft 172 and is urged toward the ratchet by means of a coil tension spring 173.

Each step movement of the ratchet wheel causes a step movement of the tenths minute wheel 28 through a transmission including the gear 174 rotatable with the ratchet wheel 26 and a gear 175 rotatably mounted on a shaft 176 and rotatable with the tenths minute wheel 28. The units minute wheel 29, the tens minute wheel 30, the hour and meridian wheel 31 and the day of the month wheel 32 are all driven and locked in train from the tenths minute wheel 28 by means of Geneva gearing. Thus the units minute wheel 29 is driven from the wheel 28 by means of the single tooth Geneva gear 177, the star wheel 178 and the gear 179 meshing with the star wheel 178 and mounted on the sleeve 180 on which the gear 29 is mounted. The printing wheel 30 is driven from the gear 29 by means of the single tooth Geneva gear 181, a star wheel 182 driven by this single tooth gear, a pinion 183 rotatable with the star wheel, and a gear 184 secured to rotate with the printing wheel 30. The hour wheel 31 is driven from the printing wheel 30 by a Geneva friction drive by means of a two-tooth Geneva gear 185 rotatable with the

wheel 30. A star wheel 186 driven by the Geneva gear, a pinion 187 rotatable with the star wheel, a gear 188 meshing with the pinion 187 and a three-armed spring friction member 189 secured 5 to rotate with the hour wheel 31. The three spring arms 189 (Figs. 15, 16 and 17) of the friction member cooperate with a circular series of teeth 191 struck up from the gear 188 so that as the gear is turned the friction member will 10 turn therewith and thus cause the movement of the hour wheel 31. This slip connection of the wheel 31 with the gear permits the hour wheel 31 to be set independently of the movement of the preceding printing wheel of the train by 15 means of a setting shaft 192 (Fig. 20) having a key-engaging portion 193 and having mounted thereon a pinion 194 meshing with a gear 188 which rotates with the hour wheel 31 secured thereto by means of rivets 186. The day of the 20 month wheel 32 is driven from the hour wheel 31 by means of a slip friction drive including the single tooth Geneva gear 197 secured to the hour wheel 31 by means of the rivet 186, a star wheel 198 driven from this Geneva gear, a pinion 199 25 rotatable with the star wheel, a gear 200 meshing with this pinion, and a three-armed spring friction member 201 (Figs. 18, 19 and 28) secured upon the hub 202 of the day of the month wheel 32 and having its three spring arms 203 yielding- 30 ly engaging a circular series of teeth 204 on the gear 200 in a manner similar to that described in connection with the spring friction drive for the wheel 31. This day of the month wheel 32 may be set independently of all of the preceding 35 printing wheels of the train by means of a setting shaft 205 having a key-engaging end 206 and having mounted thereon a small pinion 207 which meshes with a gear 208 secured to rotate with the day of the month wheel by means of 40 eyelets 209. It will thus be seen that both the hour wheel 31 and the day of the month wheel 32 may be set independently of each other and all of the preceding printing wheels of the train without, however, interfering with the operation 45 by which all of the printing wheels 28, 29, 30, 31 and 32 are driven and locked in train from the ratchet wheel.

The clock mechanism is driven from the gear 174 (Fig. 2) by means of a gear 210 meshing 50 with this gear, a shaft 211 on which the gear 210 is mounted, a worm 212 secured on this shaft 211 and worm wheel 213 meshing with this worm 212 and mounted on the main center drive shaft 214 for the clock hands 215 (Fig. 6). 55 The month wheel 33 and year wheel 34 are set independently of the printing wheels 28 to 32, inclusive, by hand by means of the key operated setting shaft 35 (Fig. 2) which has mounted thereon a pinion 216 meshing with a gear 217 60 rotatable with the month wheel 33. The month wheel 33 drives the year wheel 34 through a single tooth Geneva gear 218 mounted on a sleeve 219 which rotates with the month wheel 33 and drives a star wheel 220 rotatable with a 65 pinion 221 meshing with a gear 222 secured to the year wheel 34.

In order to enable the five printing wheels, 28 to 32, inclusive, to be set by means of a key, independently of the movement of the ratchet wheel 26, an aligning disconnecting clutch is 70 provided between the ratchet wheel 26 and the gear 174 which drives the set of printing wheels. This independent setting construction comprises a number of pins 223 (Fig. 2) on the gear 174 75 which fit into corresponding recesses in the align-

ing clutch plate 168 secured to the hub 224 on which the ratchet 26 is mounted. The clutch plate 168 may, however, be disengaged from the pins 223 by axial movement as the hub is mounted on a sleeve 225 which is axially shiftable on the shaft 226 on which the gear 174 is mounted. The clutch plate 168 is normally urged to its clutch position by means of a coil spring 227 having one end seated against a collar 228 riveted to the shaft 226, and its other end bearing 10 against the shoulder 229 on the axially shiftable sleeve 225. The axial shifting of the clutch plate 168 to disengage the clutch plate from the pins 223 is effected by means of an axially shiftable plate 230 having secured thereto a pair of pins 15 231 which extend through openings in the gear 174 and the ends of which bear against the clutch plate 168. This clutch-releasing plate 230 has a pair of semi-circular openings to receive the split portions 232 on the shaft 226 on which the 20 gear 174 is mounted, the plate being provided with a bridge portion 233 lying between the split portions of the shaft to be engaged with the flattened end 234 of a setting key 235 which may be inserted in the keyhole 236 and pressed inwardly to move the clutch-releasing plate 230 axially, thus shifting the clutch plate 168 axially also and releasing the pins 223 on the gear 174 from the recesses on the clutch plate 168.

When this release has been effected the gear 30 174 may be moved independently of the ratchet wheel 26 to set the train of printing wheels, the clock hands being set at the same time through the gear train previously described.

Ribbon feed

The ribbon feed is effected by means of a rock arm 237 (Fig. 3) pivotally mounted at 238 on the stamp head 3 and carrying a pawl 238^a which drives a ratchet 239 which, in turn, drives one 40 or the other of the gears 240 which drive the ribbon spools 241 (Fig. 11). In order that the resistance offered by the feeding movement of the ribbon may not act as a drag to slow up the downward movement of the stamp head an arrangement is made whereby the actual feeding of the ribbon is on the up stroke or return stroke 45 of the stamp head, this being accomplished by arranging so that the end of the rock lever will strike an abutment 242 on the upper casing section 1 on its return movement, thus causing a movement of the rock arm relative to the stamp head and causing the pawl on the rock arm to advance the spool ratchet wheel one step on the upward movement of the stamp. The rock arm 50 is moved upwardly relatively to the stamp head to cause the pawl 238^a to engage a succeeding tooth of the ribbon feeding ratchet wheel 239 by means of a slide 243 mounted on the stamp head 3 and pivotally connected at 244 with the 55 rock arm 237 and having a laterally extending foot portion 245 which engages the plate 53 on the down stroke of the stamp head, thus retracting the pawl 238^a to cause it to engage a succeeding tooth on the ratchet 239. This arrangement 60 relieves the downward movement of the stamp head from the actual work of feeding the ribbon so that the movement of the stamp head is not slowed up appreciably.

It will be seen that the construction described 70 above is such that the objects of the invention recited are obtained.

The switch and associated construction shown in Figs. 21 to 29, inclusive, is substantially the same as that previously described except that 75

the switch arm operating member 21 and spring 23 are dispensed with, the spring 99 (Figs. 25 and 26) being connected at its lower end to the trigger arm 14 in such a way as to serve as a return for this trigger arm; that an adjustment is provided for varying the time of opening of the switch with respect to the position of the armature head 134 and that means are provided whereby the position of the card at the time the stamping action takes place may be varied.

The spring 19 which serves to effect a closing movement of the switch furthermore is mounted in a somewhat different manner than that shown in Fig. 7, the ends of the spring being held in place by tapering metal studs 248 with which the ends of the spring snugly engage so that perfect electrical connection is provided between the binding plate 118 and the carbon contact piece 18.

20 The adjustable means for changing the time of opening of the switch with respect to the position of the armature head 134 is shown in detail in Figs. 21 to 24, inclusive and in Figs. 31, 32 and 33. This construction comprises a yielding plunger 247 mounted for sliding movement in the wings of a bracket 248 which, in turn, is adjustably mounted on the front guide plate 142 secured to the armature head 134. The adjustment of this bracket 248 on the guide plate 142 is effected by 25 means of an eccentric 249 operating in a transversely extending notch 250 in the bracket 248 and swiveled on a stud 251 secured to the plate 142. The eccentric 249 is held in adjustable position by means of a lock nut 252 threaded on the stud 251. The bracket 248 is mounted for up-and-down sliding movement on the plate 142 by means of a pair of straps 253 pressed up from the material of the bracket and straddling the plate 142 as shown in Figs. 22 and 23. The 30 plunger 247 is biased downwardly by means of a coil compression spring 254 surrounding the plunger 247 and bearing at its upper end against the upper wing 255 of the bracket and at its lower end against a collar 256 formed on the plunger. The distance to which the spring can 35 force the plunger downwardly is limited by the engagement of this collar 256 with the lower wing 257 of the bracket. The lower end of the plunger extends through the lower wing 257 into 40 position to engage the rearwardly extending arm 258 of the switch arm 18 (Fig. 25) and corresponds to the pin 20 in the modification shown in Fig. 6.

By means of the above described construction, 45 the amount of energy furnished to the stamp actuating solenoid coil 6 may be varied as desired and thus the vividness of the impression made may be controlled. Thus, if the eccentric cam 249 is adjusted to bring the switch opening plunger 247 to its lowermost position, the switch will be opened at a relatively early stage in the movement of the armature head 134 and the amount of current supplied to the solenoid coil 6 will be relatively small, thus resulting in a 50 relatively light printing impression. Furthermore, as this cut-off of current is effected at a time in which the armature head 134 is relatively distant from the solenoid, the effect of the flow of the current on the armature head will 55 be still further lessened so that the actual energy which is effective on the armature is dependent not only on the duration of the flow of current but also on the distance of the armature head 134 from the coil 6. To get a stronger impression, the eccentric would be adjusted to raise the posi-

tion of the switch opening plunger 247, thus allowing the current to flow for a longer time and to cut off at a position in which the armature head 134 is relatively close to the coil 6.

This ability to vary the strength of the printing impression is highly desirable, as it enables the stamp to be adjusted to take care of various conditions met in commercial use.

In order to vary the printing position of the card, a number of alternatively usable finger tips 258, 260, and 261 are provided for the switch operating arm 14, as shown in Figs. 25, 28, and 29. These finger tips are so designed as to be readily attachable and detachable with respect to the switch arm 14. For this purpose the switch arm 15 is provided with three headed studs 262, 263, and 264 which may be engaged by the lower portion 265 of the finger tip. This lower portion is bent at its lower end at 266 to engage the rounded surface of the lower stud 264 so as to securely 20 position the finger tip. The upper ends of the finger tips are made in different designs so that the printing position of the paper may be varied. Thus, the paper-engaging portion 267 of the finger tip shown in Fig. 28 is offset with respect 25 to the lower portion of the finger tip to a greater extent than is the case of that shown in Fig. 29. Both of the offsets of Figs. 28 and 29 are different from the offset shown in Fig. 25. By the use of three or four different styles of finger tips, any 30 desired printing position of the paper may be secured.

Further modifications will be apparent to those skilled in the art and it is desired, therefore, that the invention be limited only by the prior art and 35 the scope of the appended claims.

Having thus described my invention, what I claim and desire to secure by Letters Patent is:

1. A time stamp comprising a movable impression member, actuating means for said impression member, electro-magnetic means for operating said actuating means, a switch controlling the circuit for said electro-magnetic means, and means furnished with motive power from the actuating means for opening the switch, said 40 actuating means comprising yielding transmission means acting on the movable impression member whereby the actuating means may complete its movement to open the switch even though the impression member is unable to complete its movement.

2. A time stamp comprising a movable impression member, actuating means for said impression member, electro-magnetic means for operating said actuating means, a switch controlling the circuit for said electro-magnetic means, and means controlled by the movement of the actuating means for opening the switch, said actuating means comprising yielding transmission means acting on the movable impression member whereby the actuating means may complete its movement to open the switch even though the impression member is unable to complete its movement, said yielding transmission comprising a spring confined under initial stress 55 whereby said actuating means must exert a force greater than this initial stress in order to move independently of the impression member.

3. A time printing device comprising a base mounting an oscillatable impression member 70 having a normal position and an impression making position, a stop for limiting the return movement of said impression member from impression making position means whereby said stop may be moved to non-stop position to per-

mit movement of the impression member in excess of its normal return movement, and a removable cover member for said impression member having provisions for effecting the movement of said stop to its stop position when said cover is assembled on said base.

4. A time stamp comprising a movable impression member, actuating means for said impression member, electro-magnetic means for operating said actuating means, a switch controlling the circuit for said electro-magnetic means, means furnished with motive power from the actuating means for forcing the switch open, and adjustable means for varying the time of opening of the switch with respect to the position of the actuating means.

5. A time printing device comprising a movable impression member, a switch, energy storing means in said switch for effecting closing movement thereof, electro-magnetic means controlled by said switch for operating said impression member and for energizing said energy storing means, and means for holding the switch in open position releasable by a sheet inserted into printing position in said device.

6. A time printing device comprising a movable impression member, electro-magnetic means for operating said impression member, a switch for controlling the circuit of said electro-magnetic means, means tending to close said switch, means furnished with motive power from said electro-magnetic means for setting and latching said switch in open position against the action of said means tending to close said switch, and means comprising a movable member operable by a sheet inserted into printing position in said device for releasing said latching means.

7. An automatic electrically-operated time printing device, comprising electrically operated time printing means, a circuit therefor, a switch and means for causing the circuit to be closed by releasing motive power stored within said switch to close said circuit, means whereby said motive power is furnished by previous closing of said switch including an electro-magnet energized thereby to cause the switch to open against a tendency to close, and means to cause said switch to be latched in open position, said last means being operable by an object inserted into printing position in said device to release said switch from latched position.

8. In an automatic stamping device, a type element and a platen element, an electromagnet and an armature therefor, a resilient connection between said armature and one of said elements, means for energizing said electromagnet to cause relative motion between said elements for the stamping operation, and means for adjusting said resilient connection to vary the strength of impact between said elements.

9. In a printing device having a frame, a type carrying member, a platen member, electromagnetic means for effecting relative movement of said members, one of said members being stationary with respect to said frame normally open contacts biased to closed position, a trigger member adapted to be actuated by the insertion of a strip in the printing position, means responsive to actuation of said trigger member for releasing said contacts to effect energization of said electromagnetic means, and means for preventing more than the desired energization of said electromagnetic means for a single insertion of a strip.

75 10. In a recorder, a printing mechanism, a

platen, a solenoid for effecting printing movement between said printing mechanism and said platen, an electric circuit for said solenoid, electric contacts interposed in said circuit, a trip device operable by the insertion of an object to be printed into printing position for releasing said contacts to close said circuit, and automatic means adapted to open said contacts during said printing movement.

11. In a recorder, electrical means for effecting a printing operation including a pair of contacts continually urged toward closed position, and a trip releasable by an object to be printed for holding said contacts in open position.

12. In a recorder, electrical means for effecting a printing operation including a pair of contacts urged toward closed position, and a trip releasable by an object to be printed for holding said contacts in open position.

13. In a printing construction, a movable impression member, electro magnetic means for actuating said impression member to effect a printing operation, a pair of contacts for controlling said electro magnetic means, spring means continually urging said contacts toward closed position, means controlled by said electro magnetic means for forcing said contacts open against the action of said spring means, and a latch for holding said contacts in open position releasable by the insertion of a strip into printing position.

14. In a device of the character described, a movable impression member, electromagnetic means for operating said impression member, a circuit for said electromagnetic means including a normally open switch, a normally restrained energized element tending to close said switch, means operated by the insertion of a strip for releasing the restraint on said element to cause closure of the circuit and operation of the impression member to make an impression on the inserted strip, and means operative concurrently with movement of the impression member for opening said switch and restoring the restraint on said element.

15. In a printing device, electrical means for performing the printing operation including a pair of contacts, normally energized energy storing means for closing said contacts, means for releasing the stored energy by a sheet inserted into printing position in said device, and means controlled by said electrical means for opening said contacts at a predetermined time during the printing operation.

16. In a printing device, an impression member having a predetermined cycle of movement to effect a printing operation, electric power means for supplying energy for the movements of said member, means controlled by said power means for storing energy during each printing operation and for cutting off the supply of power to said power means, means for utilizing the energy stored during one printing operation in controlling the succeeding printing operation, and a trigger member operable by a sheet inserted into printing position in said device for releasing the stored energy.

17. In a printing device, a movable impression member having a reciprocatory movement for effecting a printing operation, electric power means for furnishing motive power to said member, a spring, means controlled by said power means for storing energy in said spring and for cutting off the supply of power to said power means, means for utilizing said stored energy in

- controlling a subsequent printing operation of said member, and trigger means operable by a sheet inserted into printing position in said device for releasing the energy stored in said 5 spring.
18. Time impression apparatus comprising a movable impression member, electric power means for causing movement of said impression member, a switch for controlling the current for 10 said electric power means, means for causing closing movement of said switch comprising energy storing means stored with energy supplied by said electric power means, means for latching said energy-storing means in energy-storing condition, and means operable by a sheet inserted into printing position in said apparatus for operating said latch means to release said energy-storing means to cause closing movement of the switch.
- 15 19. Time impression apparatus comprising a movable impression member, electric power means for causing movement of said impression member, a switch for controlling the current for 15 said electric power means, means for causing closing movement of said switch comprising energy storing means stored with energy supplied by said electric power means, means for latching said energy-storing means in energy-storing condition, trigger means operable by an inserted 20 sheet for operating said latch means to release said energy-storing means to cause closing movement of the switch, and means controlled by movement of said electric power means for causing said switch to open and said energy-storing means to be moved to and relatched in energy-storing position.
- 25 20. Time impression apparatus comprising a movable impression member, electric power means for causing movement of said impression 25
- member, a switch for controlling the current for said electric power means, means for causing closing movement of said switch comprising energy storing means stored with energy supplied by said electric power means, means for latching said energy-storing means in energy-storing condition, manually operable means comprising a member movable from one position to another for operating said latch means to release said energy-storing means to cause closing move- 10 ment of the switch, and means controlled by movement of said electric power means for causing said switch to open and said energy-storing means to be moved to and relatched in energy-storing position in either position of said manually operable member, said manually operable member being in position to be operated by the edge of a sheet on which an impression is to be made.
21. In an automatic stamping device, two co- 20 operating stamping elements, electromagnetic means for causing relative motion between said stamping elements to effect a stamping operation, a circuit for said electromagnetic means including a switch, means for automatically opening said switch during the stamping operation, and means for varying the strength of impact between said elements by adjusting the time of opening of said switch.
22. A time stamp comprising a two-part cas- 30 ing, an oscillatable stamp head in said casing having a normal position and a stamping position, a movable stop for limiting the movement of said stamp head in the direction away from said stamping position to restrain it from movement beyond its normal position, and means whereby said stop is moved into effective position by the act of assembling the casing sections.

ERNEST S. OSTLER.

CERTIFICATE OF CORRECTION.

Patent No. 2,214,796.

September 17, 1940.

ERNEST S. OSTLER.

It is hereby certified that error appears in the printed specification of the above numbered patent requiring correction as follows: Page 1, second column, line 39, after the word "transverse" insert --vertical--; page 5, first column, line 14, for "or" read --on--; and that the said Letters Patent should be read with this correction therein that the same may conform to the record of the case in the Patent Office.

Signed and sealed this 5th day of November, A. D. 1940.

(Seal)

Henry Van Arsdale,
Acting Commissioner of Patents.
